UNITED STATES PATENT OFFICE

DAVID A. BRYCE, OF DARIEN, CONNECTICUT

OFFICE CABINET

Application filed September 6, 1928. Serial No. 304,319.

This invention relates to the broad class of office furniture and equipment and has more particular reference to a combination record filing and treatment cabinet which is especially adapted for use in offices of doctors and analogous practitioners.

The invention has more specific reference to a structure which has the general appearance of a conventional sliding drawer record and index filing cabinet of the vertical or upright type, but which is distinguished from the ordinary cabinet, in that it embodies a special top compartment enclosing a normally concealed electrical structure for supplying electric current for various kinds of portable electrical appliances, and electrical treatment machines of the kind utilized for subjecting the body of the patient to special electrical treatments and operations.

My principal aim is to provide a structure of this general type which is characterized by unusual simplicity in construction and arrangement, compactness and convenience in disposition of parts, smooth and quiet in operation, efficient in performance, and otherwise especially adapted for fulfilling the requirements of a structure of this class in an efficient manner.

30. In the drawings:

Figure 1 is a perspective view of the complete cabinet constructed in accordance with the present invention.

Figure 2 is a central vertical sectional view through the same.

Figure 3 is an enlarged fragmentary horizontal section through the chamber containing electrical resistance elements.

Figure 4 is a fragmentary sectional view, showing a roller support for one of the sliding drawers.

Figure 5 is a fragmentary section through the rear portion of the electrical compartment.

Figure 6 is a view based on Figure 1, and showing the dual arrangement of rollers for supporting the sliding drawer.

Figure 7 is a fragmentary section through one corner of the structure showing the cas-

ing construction and one of the uprights or posts.

Figure 8 is a fragmentary section showing the hinged door stop flange.

Referring now to the drawings by reference numerals, it will be observed that the vertically elongated casing is indicated by the reference character 9, the same being formed with an open front surrounded by an inwardly bent flange portion 10 as shown in Figure 7.

This portion is bent around the semi-H-shaped corner posts 11.

As shown better in Figure 2, the lower portion of the structure is made to accommodate three sliding drawers 12, each of which is provided with an index card holder 13 on its front and an operating hand grip 14. These drawers are equipped with side rollers 15, operable in channel shaped guide tracks 16. Extending across the front is a channel shaped rest bar 17, whose top flange is provided with anti-friction rollers 18 as shown in Figures 4 and 6 to facilitate operation of the drawer.

Attention is now invited to the upper portion of the structure which includes a special electric current supply device, the principal parts of which are housed in a top compartment 19. The outer end of this compartment is closed by an upwardly swinging door 20, hinged as at 21 and provided with a card holder 22 and a hand grip 23. It thus has the general appearance of the sliding drawers therebeneath. Located in the rear end portion of this compartment is a perforated partition plate 24, forming a rear electrical chamber 25.

Referring to Figure 3, it will be seen that on top of this chamber are binding posts 26 and 27, with which lead wires 28 and 29 are connected, these being connected at their opposite ends to similar binding posts 30 and 31. The intermediate portions are coiled as at 32, around suitably supported insulation bars or rods 33, thus providing a plurality of resistance coils.

I now call attention to that portion of the compartment between the hinged door and the perforated plate 24. In this compartment and on opposite walls are upper

and lower tracks 34, and 35, respectively. A carrier is slidably mounted on the tracks. The carrier is made up of two sections, each including vertical bar members 36, connected together by cross pieces 37. The carriers are equipped with rollers 38 movable along the tracks. Connected to each portion of the carrier is an extensible lazy tong supporting device 39, equipped with longitudinal eyes 40 through which an extension wire 41, passes in the loop fashion shown in Figure 2. The wire 41 is obviously connected to the complementary binding posts 30 or 31 as the case may be. At the forward or outer end the wire is connected with a swivel or ball and socket terminal 42.

In practice, the house wires carry from one hundred and ten to one hundred and fifteen volts and are connected with the binding posts 26 and 27 to conduct current through the wires 28 and 29 of the resistance coils to the current output wires 41. By opening the door 20, access is permitted to the compartment 19, whereupon the roller supported carriages or carriers are rolled out on the track to the extreme forward ends of the tracks.

Then lazy tong devices 39 are extended and adjusted to proper position for operation. Of course the electrical appliance or treatment machine will be equipped with terminals which shall be connected with the swivel or ball and socket connections 42 on the outer ends of the lazy tong devices.

When the device is not in use, it is moved back into the compartment and the door is closed to conceal it. The records and file pertaining to the tests, examinations, and treatments are systematically filed in the sliding drawers.

The gist of the invention is in the provision of the combination cabinet, characterized by exceptional compactness and convenience to adapt it for use in small offices, particularly doctors' offices requiring the use of reduced electrical current for the operation of electrical treatment machines. The cabinet is properly constructed to render it sturdy and to make it portable and to greatly add to the facility in an otherwise crowded office, laboratory, examination room or the like.

It is thought that persons familiar with inventions of this general class will be able to obtain a clear understanding of the construction, use and advantages, upon considering the description in connection with the drawings.

Therefore a more lengthy description is regarded unnecessary. Minor changes in the shape, size and rearrangement of parts coming within the field of invention claimed may be resorted to, if desired.

I claim:

15 In a structure of the class described, com-

prising, a vertically elongated cabinet, said cabinet being formed in its top with a special compartment, tracks mounted in the compartment, a hinged door for closing said compartment, a partition plate in said compartment forming a special resistance chamber at the rear end thereof, resistance coils mounted in said chamber, and adjustable and extensible wire supporting means mounted in said compartment and including wires connected with said resistance coils, said means embodying a roller supported carrier slidably mounted on the tracks in said compartment, and lazy tong devices mounted on said carrier, said wires being connected with said devices.

In testimony whereof I affix my signature.
DAVID A. BRYCE.
